UNITED STATES PATENT OFFICE

2,581,884

THUMB GRIP NOCK

Walter D. Ringel, Monroe, Mich.

Application March 29, 1948, Serial No. 17,621

2 Claims. (Cl. 273—106.5)

1

This invention relates to an archery device and more particularly to an attachment for an arrow, which will enable the arrow to be propelled from a bow faster and more conveniently, and also enable the arrow to assume a truer and more accurate path of flight.

Another primary object of this invention is to provide an attachment for an arrow shaft, which will enable an arrow to be more conveniently and easily removed from a quiver or the like carrying case, and to be positioned in propelling placement on a bow string, with a minimum of time expended, thereby enabling a greater number of arrows to be shot from a bow in a relatively short time.

Another object of this invention is to provide a nock section for an arrow shaft, which will enable the shaft to be more conveniently positioned in propelling placement on a bow string and, also, to provide in association with the nock section means for enabling the arrow to be gripped.

Another object of this invention is to provide a thumb gripping section formed integral with the nock section, so that the arrow shaft is held on the bow string by the fingers, with the thumb serving to position and maintain the shaft in true placement, so that the shaft may be propelled a greater distance and assume a truer and more accurate path of flight.

A meritorious feature of this invention resides in the provision of an attachment for the feathered end of an arrow shaft, the attachment having a nock section including finger and thumb gripping means disposed thereon.

These and ancillary objects and other meritorious features are attained by this invention, a preferred embodiment of which is set forth in the following description and illustrated in the accompanying drawings, wherein:

Figure 1 is a perspective view of an archer, illustrating a plurality of arrows held in a quiver, each arrow being provided with an attachment, formed in accordance with the principles of this invention, whereby the arrow shafts may be more easily removed from the quiver and positioned on the bow string with a minimum loss of time;

Figure 2 is an enlarged perspective view of this invention, showing the same in use and positioned in propelling placement on a bow string;

Figure 3 is a top plan view of this invention;

Figure 4 is a side elevational view, depicting the rearwardly extending thumb gripping section, and

Figure 5 is a fragmentary elevational view of

2

this invention, showing the same in employment.

Referring now more particularly to the drawings, wherein similar characters designate corresponding parts throughout, there is shown an arrow shaft 10, of conventional structure, formed of either wood or metal or the like and having a customary feathered end 12 disposed thereon. Provided for attachment to the feathered end 12 of the shaft 10, which is substantially circular in cross-section, is a thumb-gripping nock section, 14, comprising a body portion 16 of similar configuration as that of the shaft 10, the body portion 16 being secured to the end of the shaft, as at 18, by any suitable fastening means, such as adhesive or the like. The fastening means employed may be of any type, provided the balancing of the shaft is not destroyed by additional weight at the juncture of the attached section 14 and the shaft 10.

Extending rearwardly from the body portion 16 are a pair of opposed concave sides 20 and 22, which are adapted to serve as finger-gripping sections, with reference to Figure 2 of the drawings. Extending longitudinally from the rearwardly terminating portions of the concaved sides 20 and 22 is a nock 24 defined by a pair of opposed arms 26 and 30. The arm 26 extends rearwardly a substantial distance beyond the terminating portion of the arm 30 and terminates in an end portion 28 having inwardly inclined sides. The extending arm 26 and the integral faired end 28 are adapted to serve as a thumb accommodating section, as seen in Figure 2 of the drawings.

Thus, with reference to Figure 1 of the drawings, there is shown a plurality of arrow shafts 10 retained in selected placement on an archer's back, by means of the quiver 32, the shafts 10 being provided with the finger-gripping nock section 14, as seen in Figure 3 of the drawings. Thus, it is to be noted that an archer in feeling for the arrow in the quiver merely grasps the extending handle or arm 26 and removes the arrow shaft from the quiver. With a mere twisting action, the arrow and the appurtenant nock 24 may be easily positioned on a bow string 38, as seen in Figure 2 of the drawings. In such propelling placement, an archer at all times, has perfect control of the arrow, due to the placement of the fingers in the concave sides or finger accommodating grooves 20 and 22, with the thumb positioned over the extending handle or arm 26. The tapered or inclined end 28 is adapted to snugly fit within the palm portion of the thumb, so as

to obviate the possibility of a twist being imparted to the shaft upon release of the bow string.

It is to be noted that the finger gripping sides 20 and 22 in association with the thumb gripping handle 26 provide a medium for enabling an archer to maintain constant and steady control of the shaft prior to propulsion thereof from the bow.

However, since many other objects and purposes of this invention will become apparent to those skilled in the art, upon a perusal of the foregoing description, it is to be understood that certain changes may be made as coming within the spirit of the invention and the scope of the 15 appended claims.

Having described the invention what is claimed as new is:

1. In a feathered archery arrow shaft having a nock end, a pair of concave finger grip sections in opposite sides of said shaft adjacent said nock end for gripping between adjoining fingers of the hand in positioning the shaft relative to a bowstring, and a pair of opposite rearwardly extending arms on said nock end spaced apart to form therebetween a bowstring receiving nock, one of said arms being longer than the other and extending rearwardly thereof for gripping be-

tween the thumb and palm of the hand while said fingers grip said sections and whereby to facilitate holding the shaft by the hand.

5 2. A feathered archery arrow shaft according to claim 1 wherein said longer arm is provided with a beveled end fitting against the palm of the hand to prevent the shaft from turning in the hand.
